ATTORNEY

UNITED STATES PATENT OFFICE

172,263

PLATE OR SIMILAR ARTICLE

A. Baker Barnhart, New York, N. Y., assignor to
The Rosenthal-Block China Corporation, New York, N. Y.

Application March 30, 1953, Serial No. 24,267

Term of patent 7 years

(Cl. D44—15)

To all whom it may concern:

Be it known that I, A. Baker Barnhart, a citizen of the United States, residing in the city of New York, county of New York, State of New York, have invented a new, original, and ornamental Design for a Plate or Similar Article of which the following is a specification, reference being had to the accompanying drawing, forming a part hereof.

The figure is a plan view of a plate or similar article of conventional configuration, showing my new design.

I claim:

The ornamental design for plate or similar article, as shown and described.
